(57) **CLAIM**

The ornamental design of a portion for a floor cleaner foot, as shown and described.

DESCRIPTION

FIG. 1 is a front elevational view of a portion of a floor cleaner foot showing our new design;

FIG. 2 is a top view thereof;

FIG. 3 is a front view thereof;

FIG. 4 is a left view thereof; and,

FIG. 5 is a right view thereof.

The details shown in broken lines form no part of the claimed design.
